PACKAGING TRAY FOR CANDY

Richard Gibian, Box 879, Selma, Ala. 36701, and
Maurice Bernard, 1247 Zonolite Road NE., Atlanta,
Ga. 30306

Filed Feb. 22, 1973, Ser. No. 334,604

Term of patent 14 years

Int. Cl. D9—03

U.S. Cl. D9—189

Fig. 1

Fig. 2

Fig. 3

Fig. 4

Fig. 5

FIG. 1 is a top plan view of a packaging tray for candy showing our new design;

FIG. 2 is a bottom plan view;

FIG. 3 is a side elevational view, the opposite side being the same in appearance as the side shown;

FIG. 4 is an end elevational view, the opposite end being the same in appearance as the end shown; and

FIG. 5 is an enlarged fragmentary sectional view taken on the line 5—5 of FIG. 1.

We claim:

The ornamental design for a packaging tray for candy, substantially as shown and described.
